Patented Aug. 6, 1912.

UNITED STATES PATENT OFFICE.

ALLEN CHEEVER WRIGHT, OF BERKELEY, CALIFORNIA.

APPARATUS FOR SEPARATING AND COLLECTING PARTICLES OF ONE SUBSTANCE SUSPENDED IN ANOTHER SUBSTANCE.

1,034,668.

Specification of Letters Patent. Patented Aug. 6, 1912.

Application filed October 24, 1911. Serial No. 656,520.

To all whom it may concern:

Be it known that I, ALLEN CHEEVER WRIGHT, a citizen of the United States, residing at Berkeley, in the county of Alameda and State of California, have invented certain new and useful Improvements in Apparatus for Separating and Collecting Particles of One Substance Suspended in Another Substance, of which the following is a specification.

My invention relates to apparatus for use in the art of separating mechanical mixtures, or mixtures of liquids and solids; and particularly to that type of treating device in which the mixture is subjected to the action of an electric field between charged electrodes.

My invention consists in novel features of construction, arrangement and combination of an apparatus or treater of this type, which I shall hereinafter fully describe, said features having for their general object a more efficient separation with less expenditure of electrical energy. Their special objects, and the manner in which these are attained will be fully understood from the following description, and by reference to the accompanying drawings, in which—

Figure 1 is a vertical sectional view of my apparatus. Fig. 2 is a cross section on line $x-x$ of Fig. 1.

1 is the shell which is best formed of a pipe of circular section. To the base of the shell is secured the foot plate 2, which rests upon friction wheels 3, one or both of which being driven, impart rotation to said shell. These means for rotating the shell are merely illustrative; any suitable means may be employed.

4 are ribs on the inner surface of the shell. These are best arranged in a helical course as seen in Fig. 1. They are separated from each other by equal spaces, as in Fig. 2, and in practice are best formed upon a lining sheet 5, which fits snugly the inner surface of the shell.

6 is the inlet pipe for the mixture to be treated, said pipe leading into the shell through its foot plate 2. 7 are outlet pipes, seated radially in the head plate 8 of the shell, and adapted to discharge the lighter of the two components of the mixture from the central region thereof. 9 are outlet pipes from the peripheral region of the mix-

ture. These latter pipes are secured in the 55 foot plate 2 and thence extend downward and are inclined centrally to and fitted into what may be termed a dual head 10 to which the inlet pipe 6 is also fitted. The dual head 10 is rotatably fitted upon a non-rotatable pipe 11 with the upper end of which the outlet pipes 9 communicate. The lower end of the pipe 11 communicates with a discharge pipe 11', which is carried upward and has its outlet at a point where the columns of the components of the liquid under treatment balance each other. Through the pipe 11 rises the feed pipe 6', which enters and discharges into the inlet pipe 6.

The shell 1 constitutes the outer electrode. 70 The inner electrode is designated by 12. It is an air tight hollow metal cone with a central longitudinal channel 13. The cone is inverted and its base for a distance is cylindrical so that when said cone is in the 75 axis of the shell 1, the surface of the cone from its lower end toward its upper end converges toward the inner surface of the shell, and then extends parallel therewith. This inner electrode has a gravity slightly 80 less than that of the liquid in which it is immersed, and as it is not connected with the outer shell, it floats in the liquid; and, due to the rotation of the shell and to the vortex formed in the liquid contained in 85 said shell, which vortex is governed in size by the speed of rotation, the said inner electrode automatically assumes and maintains a position directly in the axis of rotation, so that it is self centering.

In order to hold the buoyant inner electrode down and to maintain its correct elevation, there is a metal rod 14 which is secured to and is insulated from the head plate 8 of the shell 1 by a glass or other insulating tube 15, said rod passing freely down into the central channel 13 of the inner electrode, and having its lower end arranged to receive the contact of the lower end of said electrode. The upper end of 100 the rod 14 is in electrical contact with a non-rotatable extension rod 16. Contact springs 17 secured to the rod 14 are adapted to bear upon the upper end of the inner electrode, and thus effect electrical connection. The 105 shell 1, which is the outer electrode, is electrically connected to the ground at 18 by a wire from the non-rotatable connection be-

- low, and is also connected by the wire 19 and brush 19' to one of the high potential terminals of the step-up transformer T. The other high potential terminal of the 5 transformer is electrically connected to the inner electrode 12 by a wire 20 to the extension rod 16. The low potential terminals of the transformer are connected in any suitable manner with the source of electricity, as, for example, through the inductive reactance at R.
- 21 is a suitable vessel to receive the lighter component of the mixture from the outlet pipes 7.
- 15 22 are bearing guides for the shell 1.
- For the sake of convenience, I shall describe the use of the apparatus in connection with the separation and removal of water particles from crude petroleum, but 20 it is to be understood that I do not limit my claims to this use, nor to this particular case. In an emulsion of water in oil, such as is found in much of the crude petroleum as it comes from the wells, the drops of 25 water vary greatly in size from those easily visible to the naked eye to a minuteness lying at the extreme range of vision of the most powerful microscope. The older processes of settling, centrifuging and distillation, were not, for one reason or another, 30 very satisfactory, but the later improvement of subjecting the emulsion to the action of a powerful electric field, was and is found to be quite efficient in de-emulsifying 35 the mixture, and causing the water drops to coalesce and agglomerate into larger masses which may then be separated out and removed.
- 40 In my present apparatus, I still retain the advantages of the electric treatment, but I supplement it with other beneficial features, which on the whole result in even more efficient separation with a less expenditure of electrical energy. The apparatus is given 45 a rotary velocity, say, for example, 300 to 500 revolutions per minute. The mixture enters through the pipe 6. Some of the particles of water, which are large enough, 50 are thrown out by the centrifugal action prior to entering the electrical field which is maintained between the two electrodes, but when the mixture enters said field, the 55 agglomeration of the water particles takes place under the electrostatic influence, up to the moment when the difference in gravity of the suspended particles, aided by the centrifugal action is sufficient to overcome the viscosity of the oil. Then the water particles so separated out and agglomerated 60 will be thrown out to the inner wall of the shell 1 and will flow down to the outlet pipes 9. In this way the separation takes place by the most direct route, and with a consequent minimum expenditure of electrical energy, without interfering with the

natural inclination of flow of either liquid, viz:—upward for the oil and downward for the water. Centrifugal action also introduces another advantage not possessed by the electrical treatment alone, in that it tends to throw off with the water, such solids or other foreign matter as may be held in suspension independently of the water, and which are in themselves not affected by the electrostatic forces, thus effecting a more complete clarifying of the oil than if it were subjected to the electrostatic forces alone. It will be observed that the spacing of the two electrodes is not parallel except for a short distance at the 70 upper portion. This arrangement has the beneficial effect, due to the upward direction of the flow of the material between the electrodes and the projection horizontally therefrom of the agglomerated water particles, of 75 increasing the dielectric strength of the oil; and hence the electric field between the electrodes is kept more nearly uniform.

The advantage of the automatic or self-centering floating inner electrode 12 is that under centrifugal action, it assumes and maintains the proper relation or position to the outer electrode or shell 1, without the assistance of mechanical means, other than that of the slight downward pressure exerted by the rod 14, sufficient to overcome its buoyancy and to keep it in its correct 90 horizontal position.

The discharge outlets 7 of the oil, being at the top of the treater, insure the maximum degree of separation. It will be noted that these outlets are held in seats in the head plate 8 in such manner that by loosening the bolts of said plate said pipes may be slid out or in radially. By thus adjusting them, the depth of the vortex in the liquid contained in the device may be governed.

The discharge outlets 9 are brought in toward the axis of revolution, for the purpose of giving an outlet for the water content of such nature that the water upon reaching the vicinity of the axis of rotation, permits the separation and rise of any of the oil particles which may have accompanied said water. This separation is further increased by the injector action of the incoming oil. This direction of said outlets is rendered possible by carrying them downward to a point below that where the 110 centrifugal action is overcome by the gravity head. To still preserve sufficient downward pressure on the water to overcome the centrifugal force, even in cases where, because of a decrease in speed of rotation, there is a decrease in head pressure, I provide the helically directed ribs 4. These 115 positively feed the water down with a pressure sufficient to overcome the centrifugal force.

Having thus described my invention what I claim as new and desire to secure by Letters Patent is—

1. An apparatus of the described type, 5 consisting of a shell having an inlet in its lower portion for the mixture to be treated, an outlet from the central region of its upper portion for the lighter component of the mixture, and an outlet from the per- 10 ipheral region of its lower portion for the heavier component of said mixture; means for rotating said shell on its axis; a member within and spaced from the shell; and electrical connections adapted to constitute 15 said shell and member the electrodes of an electric field to which the mixture to be treated is subjected.
2. An apparatus of the described type, 20 consisting of a shell having an inlet in its lower portion for the mixture to be treated, an outlet from the central region of its upper portion for the lighter component of the mixture, and an outlet from the per- 25 ipheral region of its lower portion for the heavier component of said mixture, said last named outlet being carried downward and directed centrally below the shell; means for rotating said shell on its axis; a member within and spaced from the shell; 30 and electrical connections adapted to constitute said shell and member the electrodes of an electric field to which the mixture to be treated is subjected.
3. An apparatus of the described type, 35 consisting of a shell having an inlet in its lower portion for the mixture to be treated, an outlet from the central region of its upper portion for the lighter component of the mixture, and an outlet from the per- 40 ipheral region of its lower portion for the heavier component of said mixture, said last named outlet being carried downward and directed centrally below the shell; a helically directed rib on the inner surface 45 of the shell to conduct said heavier component of the mixture to said last named outlet; means for rotating said shell on its axis; a member within and spaced from the shell; and electrical connections adapted to 50 constitute said shell and member the electrodes of an electric field to which the mixture to be treated is subjected.
4. An apparatus of the described type, 55 consisting of a shell; means for rotating said shell; a member within and free of the shell, and buoyant in the mixture under treatment, whereby said member is adapted, under the rotation of the shell, to assume and maintain a position in the axis of rotation; and electrical connections adapted 60 to constitute said shell and member the electrodes of an electric field to which the mixture to be treated is subjected.
5. An apparatus of the described type, 65 consisting of a shell; means for rotating said shell; a member within and free of the shell, and buoyant in the mixture under treatment, whereby said member is adapted, under the rotation of the shell, to assume and maintain a position in the axis of rotation; a stop secured to the shell and acting upon the buoyant member to define the limit of its rise; and electrical connections 70 adapted to constitute said shell and member the electrodes of an electric field to which the mixture to be treated is subjected.
6. An apparatus of the described type, 75 consisting of a shell; means for rotating said shell; a member within said shell and separated therefrom by a space which narrows from the lower toward the upper portion; and electrical connections adapted to constitute said shell and member the electrodes of an electric field to which the liquid to be treated is subjected.
7. An apparatus of the described type, 80 consisting of a shell having an inlet in its lower portion for the mixture to be treated, an outlet from the peripheral region of said lower portion for the heavier of the components of the mixture, and an outlet pipe 85 in its upper portion for the lighter of said components, said outlet pipe being arranged to be radially adjusted to different positions relatively to the axis of the shell; means for rotating the shell; a member within and spaced from the shell; and electrical connections adapted to constitute said shell and member the electrodes of an electric field to which the mixture to be treated 90 is subjected.
- In testimony whereof I have signed my name to this specification in the presence of two subscribing witnesses.
